UNITED STATES PATENT OFFICE.

EDMUND HOFFMAN, OF NEW YORK, N. Y.

DESIGN FOR A SHEET-METAL CAN.

No. 38,287.

Specification for Design.

Patented Oct. 16, 1906.

Application filed December 12, 1905. Serial No. 291,490. Term of patent 3½ years.

To all whom it may concern:

Be it known that I, EDMUND HOFFMAN, a citizen of the United States, residing at the borough of Brooklyn, county of Kings, city and State of New York, have invented a new, original, and ornamental Design for a Sheet-Metal Can, of which the following is a specification, reference being had to the accompanying drawing, forming part thereof.

Figure 1 is a side view of a can embodying

the new, original, and ornamental design of my invention. Fig. 2 is an edge view of the same. Fig. 3 is a plan view of the same.

I claim—

The ornamental design for a sheet-metal can, as shown.

EDMUND HOFFMAN.
